UNITED STATES PATENT OFFICE

SAMUEL DOWINSKY, OF NEW YORK, N. Y.

APPARATUS FOR FORMING AND FINISHING SCALLOPED EDGES OF GARMENTS

Application filed May 12, 1931. Serial No. 536,771.

This invention relates to apparatus for forming and finishing parts of certain articles of wearing apparel, namely the scalloped edges of garments.

Such scallops are formed by machine stitching two pieces of woven textile fabric together, producing the desired design, trimming away the material beyond the row of stitches and then turning the article to present the seam inside the article thus formed.

Thereafter the article is pressed on the reversed outer side, which now becomes the face, the pressing operation being ordinarily performed by hand in the presence of heat and moisture, thus enabling the finished scallops to present a neat and attractive appearance.

It is an object of the present invention to provide means whereby each individual scallop, irrespective of shape or size, may be automatically distended, formed, smoothed and completely finished at a single operation.

A further feature is in the provision of a device on which the scallop is stretched, the device being provided with a supply of moisture in the form of steam in combination with a source of internal heat.

Another aim is to produce a device of simple character, easily operated and effective in operation.

These advantageous objects are attained by the novel construction and combination of parts hereinafter described and illustrated in the accompanying drawing, forming a material part of this disclosure, and in which:—

Figure 1 is a front elevational view of an embodiment of the invention.

Figure 2 is a side elevational view of the same partially in section.

Figure 3 is an enlarged partial front elevational, partial longitudinal sectional view of the operative head of the appliance.

Figure 4 is a transverse sectional view of the three-way valve used to control the conduit from the tank.

Figure 5 is an enlarged front elevational view of the work receiving head showing its use.

The apparatus comprises a stand having

a foot 10 attached to any convenient level surface, as a bench or table, and an upright 11 enveloped on its rear side and lateral edges in a sheet metal partial casing 12.

The casing is enclosed in a box-like frame 13, at a point spaced from the foot 10, the frame having a cover 14 attached by screws 15 which pass through the upright and casing, clamping these several elements rigidly together.

The cover 14 extends upwardly and is formed into an abutment 16, extending over the top of the frame, terminating in a former 17 gradually tapering to thin top and side edges the profile of which is suited to shape of the scallop to be drawn over it as best seen in Fig. 5.

Secured to the rear surface of the frame 13 is an arm of a support 18 terminating in a support bracket 19 on which is fixed a tank 20 provided with a perforate cover 21 removably engaged thereon.

Set in the bottom of this tank 20 is a nipple connecting a straight-way valve 22, its opposite end engaging connections, including a union and leading to a three-way valve 23 controlled by a plug 24, the valve having two lateral openings which may be connected by a fine arcuate groove 25 in the plug so that either or both orifices may be used to dispense liquid from the tank.

Connected with these orifices are small tubes 26 leading to the lower ends of coils 27 set in the frame 13, the upper ends 28 of these coils entering openings in the under side of the abutment 16 and connecting with passages therein to emerge in the form of minute streams through vents 29 disposed in pairs at each side of the former 17.

An electric current is used to produce heat by which the streams of entering water are turned into steam prior to escape, the current being connected to a binding post 30 set in the rear of the casing 12, adjacent an outlet binding post 31, both posts being insulated from the casing and connected to a high resistance coil 32 closely adjacent the water coils 27 to conduct heat to them.

It will be understood that suitable insula-

tion media is provided to prevent short circuiting or loss of current and it will be obvious that the fine streams of water, which entered the coils 27, from either or both sides of the valve 23 from the tank 20 are turned 5 into steam during their travel and supply the necessary moisture, while the electric coil dispenses such heat as may be necessary.

It is also to be understood that the former 10 17 may be removed and another of different size or configuration substituted without disturbing either the heating or steaming coils.

In operation the trimmed scallops are inverted and placed by hand on the former 17, to be drawn snugly thereover, as seen in Fig. 15 5, no hand ironing being necessary to produce the proper appearance and the operation may be rapidly and safely performed with unskilled labor without danger or delay.

Although the foregoing is descriptive of 20 20 the preferred embodiment of the invention, it will be apparent that minor changes may be made in its construction, without the exercise of invention or conflicting with the scope of the claim hereto appended.

25 Having thus described the invention, what is claimed as new and desired to be secured by Letters Patent, is:—

30 A finisher for woven textile fabric scallops comprising a fixed frame, a scallop former removably engaged thereon, an electric heating coil for said former, a pair of coiled tubes adjacent said coil, and means for supplying said tubes with water.

35 In testimony whereof I affix my signature.
SAMUEL DOWINSKY.
